DESCRIPTION

FIG. 1 is a front elevational view of the fastening member of the present invention;

FIG. 2 is a rear elevational view of the fastening member of FIG. 1;

FIG. 3 is a top view of the fastening member of FIG. 1;

FIG. 4 is a bottom view of the fastening member of FIG. 1;

FIG. 5 is a right side view of the fastening member of FIG. 1;

FIG. 6 is a left side view of the fastening member of FIG. 1; and,

FIG. 7 is a perspective view of the fastening member of FIG. 1.
